OVERHEAD LIGHTING, SOUND-ABSORBING, HEATING, AND AIR CONDITIONING

George P. Wakefield, Vermilion, Ohio, assignor, by mesne assignments, to The Wakefield Company, Vermilion, Ohio, a corporation of Ohio

Application February 23, 1954, Serial No. 411,768

5 Claims. (Cl. 98—40)

The present invention relates generally as indicated to an overhead lighting, sound-absorbing, heating, and air conditioning system affording pleasing environmental conditions such as over-all, diffused illumination for visual comfort, sound-absorption for auditory comfort, and diffusion heating and air conditioning for draft-free personal comfort. In addition, this system may include features concerning personal safety as, for example, fire protection.

Certain aspects of this invention are, in a broad sense, covered by my Patent No. 2,659,807 dated Nov. 17, 1953, insofar as the overhead lighting structure, as such, and its combination with heating or air conditioning is concerned, and by the Herbert L. Beckwith Patent No. 2,659,808 dated Nov. 17, 1953, insofar as the combination of an overhead lighting structure with sound-absorption and/or with heating and air conditioning is concerned.

However, the present invention progresses beyond the contemplations of the aforesaid patents in the unique arrangement of the heating and ventilating duct work in combination with the illumination and sound-absorption features of the system so that neither the illumination nor the sound-absorption is impaired in efficiency but instead is, in some respects, enhanced.

It is one main object of this invention to provide a unitary structure having a high degree of flexibility to accommodate daily and seasonal changes in heating and ventilating requirements.

Another object of this invention is to provide an overhead system as aforesaid wherein the heating and ventilating requirements may be readily modified according to the use to which the room space therebeneath is put.

Another object of this invention is to provide an overhead system as aforesaid which, in new construction, provides a facile and economical manner of finishing off a room space, or, in fact, the entire floor area of a building, to provide (a) overall, diffused illumination of desired intensity throughout the entire area or selected portions thereof; (b) efficient sound-absorption throughout the entire area or selected portions thereof; (c) controlled heating and air conditioning for the entire area or selected portions thereof; and (d) subdivision of the entire area or selected portions thereof into separate room of varying sizes, the latter feature being achieved as by means of partitions detachably supported by the overhead structure.

Another object of this invention is to provide an overhead system as aforesaid which may be easily and quickly installed and which, in its preferred form, involves only the following steps:

(1) Mounting of trunk ducts for heating and air conditioning to the roof trusses or ceiling proper of the room area;

(2) Suspending lighting fixtures in spaced relation below said trunk ducts;

2

(3) Suspending a support framework for light-diffusing panels and sound-absorbing baffles from said lighting fixtures;

(4) Connecting flexible ducts from said trunk ducts to air outlet ports in said framework; and

(5) Mounting light-diffusing panels and sound-absorbing baffles to said framework.

Another object of this invention is to provide an overhead system of the character indicated which includes a light-diffusing sub-ceiling area through which daylight may be admitted into the room as by means of windows or glass block walls disposed above said sub-ceiling, whereby the south, the west, and the east walls of the building need not have any window areas at all below the sub-ceiling. Thus, there is no problem of pulling shades, closing Venetian blinds, etc. to cut out the glare of sunlight and the necessity of relying continuously on artificial lighting. In other words, diffused daylight, as aforesaid, and direct daylight through north wall windows will be used, at time, to replace or to augment artificial lighting.

Another object of this invention is to provide an overhead system of the character indicated wherein the supporting framework for the light-diffusing panels provides detachable connections for partitions and sound-absorbing baffles, and further provides air supply openings for uniform diffusion of heating or cooling air downwardly into the room area therebelow.

Another object of this invention is to provide an overhead system of the character indicated wherein there are provided two sources of heating or cooling air supply, one from trunk ducts communicated with selected perforate acoustical baffles, and the other from a large plenum space through other perforate acoustical baffles.

Other objects and advantages of the present invention will become apparent as the following description proceeds.

To the accomplishment of the foregoing and related ends, the invention, then, comprises the features herein-after fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a transverse cross-section view through a one story office building equipped with the present overhead lighting, sound-absorbing, heating, and air conditioning system;

Fig. 2 is a horizontal cross-section view of the Fig. 1 system, such section having been taken substantially along the line 2—2, Fig. 1;

Fig. 3 is a horizontal cross-section view on a somewhat enlarged scale taken above the support framework for the acoustical baffles and light-diffusing panels, such section being indicated by the line 3—3, Fig. 1;

Fig. 4 is a perspective view of a portion of the support framework for the acoustical baffles and light-diffusing panels, showing connection of an air supply duct to said framework;

Fig. 5 is an enlarged cross-section vertically through the support framework and acoustical baffle mounted thereto to show the flow of air from the air supply duct through the perforated acoustical baffle casing;

Fig. 6 is a perspective view of a modified form of the support framework and air-diffusing baffle; and

Fig. 7 is a diagrammatic cross-section view of a modification wherein diffused daylight may supply a portion of the illumination requirements.

3 General structure

Referring now more specifically to the drawings, and first to Fig. 1, the one-story office building 1 here shown is 40 ft. wide and has vertical side walls 2 which, at their upper end portions, support roof trusses 3 for the roof 4. The distance between the floor F and the bottom chords of said trusses 3 may be, for example, between 14 and 15 ft., and in one specific example, this distance was 14' 5 $\frac{1}{2}$ ". The distance from the floor F to the bottom of the light-diffusing panel and acoustical baffle support framework 5 was 9' 2 $\frac{1}{2}$ ".

The roof trusses 3 may be spaced apart, for example a distance of 4 ft., and hung from the bottom chords thereof are a plurality of air supply trunk ducts 6, 7, 8, and 9 which will presently be described in detail in connection with Fig. 2.

Also hung from said roof trusses 3 as by means of hanger rods, wires, or equivalent means 10 are a parallel series of electrical channels 11 which, in the case of 4 ft. spacing of said roof trusses 3, would accommodate 4 ft. long fluorescent tubular illuminators 12 having their ends fitted in sockets 14 carried by said channels 11. Thus, the 4 ft. long illuminators 12 would extend in parallel rows lengthwise of the building which, in this case, is 120 ft., the lamps 12 preferably being spaced 16 in. apart and approximately 3 ft. below the bottom chords of the roof trusses and approximately 1' 9" above the light-diffusing panels 15 to be presently described.

Then, hung from said electrical channels 11 again as by means of suspending means such as hanger rods, wires, or the like 16, are a series of downwardly-opening channels 17 at 4 ft. intervals. Another series of channels 18, also spaced apart 4 ft., extend lengthwise of the building to form with channels 17 a grid-like framework 5, the intersections of which consist of couplings 19 to which said channels 17 and 18 are joined in perpendicular relation.

Over-all diffused illumination

As already described, the lighting fixtures comprise parallel rows of electrical channels 11 spaced apart, for example, 4 ft. (to correspond with the spacing of the roof trusses 3) from which framework 5 consisting of channels 17 and 18 and couplings 19 are hung or suspended by means of the hanger rods or wires 16. Each electrical channel 11 comprises, for example, five lengths secured together in abutting relation by suitable clamp means (not shown). Each said 40-foot length of channel 11 is equipped with oppositely facing paired sockets 14 for the tubular illuminators 12. Channel spacers 20 extending crosswise between adjacent channels 11 will be secured thereto at spaced intervals therealong so as to maintain said channels in desired spaced apart, parallel relation to accommodate said illuminators. Said spacers 20 also serve as conduits for the wires which electrically join together the sockets 14 in pairs to accommodate the ends of the respective illuminators 12.

The support framework 5 briefly described above is grid-like in form having square openings therethrough which in this case are slightly less than 4 ft. (the center-to-center distance between the receiving channels 17 and 18) which constitute said framework. As best shown in Figs. 3 and 4, there is mounted in each framework opening a light-diffusing panel 15 which comprises, for example, a translucent plastic pan or plate 24 having therearound an extruded metal frame 25 as of aluminum provided adjacent one end on two opposite sides with trunnions 26 which seat in angularly disposed slots 27 formed in the adjacent receiving channels 17. Adjacent the other end of said opposite sides are latch elements 28 which cooperate with latches 29 carried by the adjacent receiving channels 17, such cooperating latch elements 28 and 29 preferably being arranged so that, when that end portion of the panel 15 is swung upwardly, from a vertical position, about the trunnions 26, the elements 28 and 29 will engage and thus

support the panel in a horizontal position; and then, when that end of the panel is forced upwardly from the horizontal position, the latch elements 28 and 29 will disengage to permit said panel to swing to a vertical position. 5 If it be desired to remove the panel 15 for cleaning or replacement, the same may be raised, when in its vertical position, and then turned in the framework opening so that the trunnions 26 clear the space between the adjacent channels 17. The panel thus can be dropped down. 10 Normally, as when relamping, it is only necessary to swing the panel 15 to a vertical position whereby a maintenance man may reach up through the framework opening to remove and replace burned out lamps 12. Such opening with panel 15 swung down, is yet large enough to permit performance of other servicing or re-arrangement in connection with the heating or cooling duct work disposed above the electrical channels 11.

As is now evident, with the light-diffusing panels 15 in place, there is provided over-all diffused illumination 15 of the entire room area from wall to wall.

Sound-absorption

The receiving channels 17 and 18 of the supporting framework 5 are open downwardly, as shown, and have their lower edges formed with inturned and upturned flanges or hook-like portions 35 in which out-turned and down-turned flanges or hook-like portions 36 of perforated acoustical baffle casings 37 are adapted to be engaged. The acoustical baffle casings 37 are preferably of a length to extend between the four-sided filler units 38 attached in depending relation to the support framework couplings 19 and through which filler units, at selected points, water supply pipes equipped with sprinklers 39 may extend.

35 The acoustical baffle casings 37 are perforated, as shown, the perforations occupying an area of approximately 25% of the surface area of the baffle. Specifically, the baffle casings 37 are each approximately 6 in. deep and 3 in. wide at the top, tapering down to approximately 1 $\frac{1}{2}$ in. at the bottom, and the perforations therethrough are of .057 in. diameter, there being approximately 96 holes per square in.

40 Within and adjacent the ends of each baffle casing 37 are flanged spacers 40 made of the same perforated sheet stock as the baffle casings, said spacers being designed to support within said casing, a pad of sound-absorbing material 41 of suitable material such as glass fibers or glass wool. The acoustic pad or filler 41 thus supported in spaced relation to the walls of the casing therearound may be approximately $\frac{1}{4}$ in. thick, so as to define openings on opposite sides thereof coextensive with the length of the baffle casing 37 of $1\frac{1}{8}$ in. width at the top, tapering to $\frac{7}{16}$ in. width at the bottom.

45 It has been found that an acoustical baffle made up as described above is efficient in absorbing sounds or noises of low, intermediate, and high frequencies, viz. in the frequency range of 125 to 4000 cycles; and although the baffle casings 37 are only about 25% open, they are substantially acoustically transparent. It is to be noted that the spacing of the acoustic filler 41 from the 50 walls of the baffle casing 37 permits cleaning, washing, repainting of the baffle casing without in any way affecting the sound-absorbing properties of the baffle as a whole.

Partitioning

65 As shown in Fig. 2, the 40 ft. by 120 ft. room area may be subdivided into numerous offices, hallways, etc. of various sizes, the length and width of each office or other space being variable in 4-foot increments corresponding with the spacing of the receiving channels 17 and 18 of the support framework 5. As best shown in Fig. 1, the partitions 45 have upper edge portions which are snugly fitted between the lower edge portions of the receiving channels 17 and 18, the lower ends of said partitions being secured to the floor F by any suitable means such as by

nailing, by bolting, etc. These partitions 45 may include glazed areas (either transparent or translucent) or may simply comprise a framework sandwiched between metal sheets.

With such removable partitions 45, it is possible to quickly and easily rearrange the space in the building and to change the sizes and numbers of offices to accommodate changes in space requirements of the various departments of the company.

Heating and air conditioning

The trunk ducts 6, 7, 8, and 9 were previously referred to and, as best shown in Fig. 2, said ducts are of conventional form and extend lengthwise of the building from a multiple-zone-type air conditioning fan unit 50 in a utility room 51 at one end of the building. Said unit 50 for a building of the size indicated has a cooling capacity of approximately 30 tons and has a steam coil for heating. The unit delivers 8500 cubic ft. per minute of air to the rooms, plus 5000 cubic ft. per minute to the plenum above the light-diffusing sub-ceiling, that is, the space above framework 5 and panels 15 thereof. This unit will be provided with a supply air duct 52 from which the air passes through a conventional filter 53 into the unit proper for heating or cooling of the air as it is desired and for conditioning the air, that is, humidifying or de-humidifying the same as conditions require. The duct 54 is the return air duct from the ceiling plenum, and the duct 55 supplies fresh air from above the roof 4. The compressor for unit 50 is indicated by the reference numeral 56.

The outside walls 2 of the building will be provided with return air grills 60 in each 4-foot bay which lead through the sill to a concentric trench (not shown) back to the multiple-zone-type air conditioning fan unit 50.

The supply ducts 6 and 9 supply either hot or cool air through 4 inch diameter flexible ducts 61 to selected portions of the offices into which the building is divided by partitions 45. In order to insure uniform diffusion of the heated or cooled air, as the case may be, into the respective offices, the 4 in. diameter flexible ducts 61 are connected to transition sections 62 connected to rectangular openings through the top web of the associated receiving channel 17 or 18. Each transition section has a damper 63 to control air flow. The air thus entering the receiving channel flows therethrough and down into the openings defined between the acoustic filler 41 and the baffle casing 37, and from such openings uniformly oozes or percolates through the perforated casing 37 into the room space. The flow of the air is best shown in Fig. 5. As previously mentioned, the multiple-zone unit 50 is arranged to deliver heated air at the rate of 8500 C. F. M., and as is customary, the trunk ducts 6 and 9 are of gradually decreasing cross-section size to insure substantially uniform flow of air through each of the flexible ducts 61, one or more of which lead into each office. As shown in Fig. 2, for example, the large general office at the upper left has nine flexible ducts 61 connected to a corresponding number of receiving channels 17 or 18.

The remaining channels 17 or 18 to which no flexible ducts 61 are connected are nevertheless provided with openings through which air in the plenum above the light-diffusing sub-ceiling may pass into the room space. Air is supplied to such plenum by means of the trunk duct 7 which has a series of openings 65 at longitudinally spaced intervals therealong, and thus heated or cooled air, as the case may be, oozes down through the remaining perforated baffle casings 37 into the respective offices; and, as aforesaid, the rate of flow of air into the plenum for the size of building herein involved is about 5000 C. F. M.

From the foregoing, it can be seen that heated or cooled air is introduced into each room from the entire

ceiling area thereof and the capacity is such that there are approximately 15 air changes per hour, the air uniformly flowing downwardly and being returned through the floor or baseboard return air grills 60 by way of the previously mentioned trench to the multiple-zone unit 50 for re-use together with fresh air taken from the roof and any excess air in the plenum.

In addition to the three trunk ducts 6, 7, and 9 just described, there is a cold deck supply duct 8 which has outlets at desired longitudinally spaced intervals therealong equipped with automatic modulating dampers 66 which are normally closed, but which modulate to open position as desired so as to prevent the room or office connected therewith from overheating. Of course, zone thermostats 67 will be provided at desired points in the building and will be operatively connected with the heating and air conditioning plant in well known manner to control the temperatures of the rooms.

Instead of supplying air to each room through all of the receiving channels 17 or 18, it is contemplated to provide openings only in certain desired receiving channels to which are connected special air diffusers which usually would not include an acoustic filler therein. Such arrangement is shown in Fig. 6 as comprising a casing 70 which quite closely resembles that of an acoustical baffle casing 37 but which has closed ends and a closed top except for an upwardly extending nipple 71 which projects up through the opening in the receiving channel 17 or 18 for connection with the transition section 62. In such diffuser 70, there is preferably provided an internal baffle 72 for equalizing the air distribution for flow into the rooms through the casing perforations. It is to be understood that these special diffusers 70 will be installed only at selected points, whereas the remaining parts of the system will have the acoustical baffles 37 therein or partitions 45.

System utilizing daylight

In the system schematically illustrated in Fig. 7, the building walls 80 are preferably windowless from the light-diffusing sub-ceiling 82 to the floor, especially the walls facing west, south, and east. Conventional office building structures usually include as much window area as possible, and as a result, on clear, sunny days, window shades or Venetian blinds are closed on the west, south, and east walls to cut out the glare of the sun, thus requiring artificial lighting to the same, if not greater, extent as on dark, cloudy days.

In the system illustrated in Fig. 7, daylight is utilized to advantage to replace or to augment the artificial lighting whenever the occasion arises, by providing large window areas or large glass block wall areas 84 extending from the light-diffusing sub-ceiling 82 to the roof 85. In the building previously described, this window area or glass block area 84 may extend around the entire building for a height of about 7 ft. the trusses 3 being about 2 ft. in depth. Of course, the wall of the building which faces north may have the usual window areas below the light-diffusing sub-ceiling because of the absence of the glare of the sun.

The daylight passing through the wall areas 84 is diffused by the sub-ceiling 82 to provide overall, diffused illumination of the room area. Suitable light reflectors 86 may be employed to illuminate the center areas of the room. When such diffused daylight is insufficient, selected lamps may be turned on to afford desired intensity of illumination.

Other modes of applying the principle of the invention may be employed, change being made as regards the details described, provided the features stated in any of the following claims, or the equivalent of such, be employed.

I therefore particularly point out and distinctly claim as my invention:

1. A combined ventilating and acoustical device suitable for attachment to the ceiling of a room, said device

comprising a hollow elongated casing having an upper imperforate wall, a lower wall, and opposite side walls; a correspondingly elongated body of sound-absorbing material disposed within said casing; said body being of thickness less than the distance between such opposite side walls and of height less than the distance between such upper and lower walls; and means supporting said body with opposite sides thereof spaced from the respective side walls and with its upper edge spaced below such upper wall; such side walls, only in the regions thereof below approximately the level of the upper edge of said body, being perforated whereby air supplied into the space between such upper wall and the upper edge of said body flows longitudinally therein, downwardly through the spaces between said body and the respective side walls, and thence outwardly through the perforated regions of such opposite side walls, the upper wall of said casing being provided with means for connection with an air supply duct.

2. The device of claim 1, characterized further in that said casing comprises a channel member constituting such upper wall and the regions of such side walls that are above approximately the level of the upper edge of said body, and a generally V-shaped member detachably secured to said channel member and constituting the perforated regions of the respective side walls and such lower wall.

3. The combination with a ceiling of a room of a framework suspended from said ceiling, said framework comprising a plurality of hollow elongated casings secured together in aligned relation to form plural horizontal rows of casings, each casing having an upper imperforate wall, a lower wall, and opposite side walls; correspondingly elongated bodies of sound-absorbing material disposed within the respective casings; said bodies being of thickness less than the distance between the opposite side walls of the respective casings and being of height less than the distance between the upper and lower walls of the respective casings; and means supporting said bodies with their opposite sides spaced from the side walls of the respective casings and with their

5
10
15

upper edges spaced below the upper walls of the respective casings; the side walls of the respective casings, only in the regions thereof below approximately the levels of the upper edges of the bodies therein, being perforated whereby air supplied into the spaces between the upper walls of the respective casings and the upper edges of the respective bodies flows longitudinally therein, downwardly through the spaces between the respective bodies and the side walls of the respective casings, and thence outwardly through the perforated regions of the side walls of the respective casings, each casing having an opening in its upper wall, and air supply ducts connected with the openings of selected casings.

4. The combination of claim 3 characterized further in that panels are supported by said framework to define a sub-ceiling area that is spaced below said ceiling, said panels extending between the unperforated side wall regions of the rows of casings, and means for supplying air into the space between said ceiling and said sub-ceiling area for flow through the openings of those casings which do not have ducts connected thereto.

5. The combination of claim 3 wherein each casing comprises a channel member constituting the upper wall and upper unperforated regions of such side walls, and a generally V-shaped member detachably secured to said channel member and constituting the perforated regions of such side walls and such lower wall.
